US00D889549S

(12) **United States Design Patent** (10) **Patent No.:** **US D889,549 S**
(45) **Date of Patent:** **** Jul. 7, 2020**

(54) **GAME CONTROLLER**

- (71) Applicant: **Ironburg Inventions Limited**,
Wincanton, Somerset (GB)
- (72) Inventors: **Duncan Ironmonger**, Suwanee, GA
(US); **Carl Jeffrey**, Gloucestershire
(GB); **Michael Parker**, Gloucestershire
(GB)
- (73) Assignee: **Ironburg Inventions Limited**,
Wincanton (GB)
- (**) Term: **15 Years**
- (21) Appl. No.: **29/662,364**
- (22) Filed: **Sep. 5, 2018**
- (51) LOC (12) Cl. **21-01**
- (52) U.S. Cl.
USPC **D21/333; D14/401**
- (58) **Field of Classification Search**
USPC D14/174, 218, 387-389, 400-418,
D14/426-431, 443, 449-450, 454, 471,
D14/511; D21/333, 363, 368
CPC A63F 13/42; A63F 13/98; A63F 13/24;
G06F 3/0338

(57) **CLAIM**

The ornamental design for a games controller, as shown and described.

DESCRIPTION

FIG. 1 is a front and top perspective view of a games controller in accordance with the present design;
FIG. 2 is a front and bottom perspective view of the games controller of FIG. 1;

FIG. 3 is a front view of the games controller of FIG. 1;
FIG. 4 is a rear view of the games controller of FIG. 1;
FIG. 5 is a right side view of the games controller of FIG. 1;

FIG. 6 is a left side view of the games controller of FIG. 1;
FIG. 7 is a top side view of the games controller of FIG. 1;
FIG. 8 is a bottom view of the games controller of FIG. 1;
and,

FIG. 9 is a detailed view taken at area 9 on FIG. 1.
The broken lines depict portions of the article that form no part of the claimed design.

1 Claim, 9 Drawing Sheets
